UNITED STATES PATENT OFFICE.

HIRAM D. MORRILL, OF NORTHFIELD, VERMONT.

STONEWORKING TABLE.

1,406,477.

Specification of Letters Patent. Patented Feb. 14, 1922.

Application filed September 27, 1920. Serial No. 413,115.

To all whom it may concern:

Be it known that I, HIRAM D. MORRILL, a citizen of the United States, residing at Northfield, in the county of Washington 5 and State of Vermont, have invented certain new and useful Improvements in Stoneworking Tables; and I do declare the following to be a full, clear, and exact description of the invention, such as will enable others skilled in the art to which it appertains to make and use the same.

This invention relates to an improved stone working table and one object of the invention is to provide a table so constructed 15 that it may be tilted to a desired angle and to further so construct the table that the upper section thereof may be rotated with the table either in a tilted or horizontal position, thus permitting a block of stone 20 to be easily handled and cut.

Another object of the invention is to so construct this table that a portion thereof may be adjustably supported at one side to permit the table to be leveled when in a 25 horizontal position.

Another object of the invention is to provide an improved means for adjusting the position of the table, the adjusting means including cam elements mounted upon shafts 30 which are rotated by a power shaft carried by the base.

Another object of the invention is to so construct this table that the latch for releasably holding the table against rotation may 35 be adjusted when in engagement with the table and thus the table given a slight adjustment after being rotated to approximately the desired position.

Another object of the invention is to provide a table which will be strong and durable and simple in operation.

This invention is illustrated in the accompanying drawings, wherein:

Figure 1 is a top plan view of the improved table, certain portions of the table and operating mechanism being indicated by dotted lines.

Figure 2 is a view showing the table in end elevation.

Figure 3 is a side elevation of the improved table.

Figure 4 is a vertical sectional view through the table taken along the line 4—4 of Fig. 1.

Figure 5 is a horizontal sectional view

through the table taken along the line 5—5 of Fig. 2.

Figure 6 is a sectional view taken along the line 6—6 of Fig. 2.

Figure 7 is a perspective view of a bar 60 engaged by one of the cam wheels of the adjusting mechanism and serving as a bracing bar.

Figure 8 is a perspective view of a bracket 65 engaged by a second cam wheel.

This improved table is provided with a foundation having side beams 1 and cross beams 2, thus providing a substantially rectangular foundation. Bolsters 3 rest upon the side beams 1 and are connected 70 by a cross bar 4 and also by a casting or angle bar 5 having ears 6 at its ends so that screws or other fasteners 7 may be passed through these ears and into the reduced end portions of the bolsters 3. It will thus be 75 seen that the bolsters will rest upon the foundation and one may be moved vertically so as to permit of adjustment for leveling the table transversely.

In order to raise one side of this base 80 formed by the bolsters 3 and cross bar 4, there has been provided a shaft 8 which extends longitudinally of the foundation and is rotatably mounted in bearings 9 carried by the cross beams 2. This shaft 8 carries 85 cam disks 10 and 11, the cam disk 10 being positioned at one end of the shaft 8 where it may engage the thickened portion 12 of the casting 5 and the cam disk 11 is positioned upon the shaft 8 where it may engage the outstanding abutment lip 13 carried by the bracket 14. This bracket 14 is provided with a base 15 through which fasteners pass to connect the bracket with one of the bolsters 3 and the outstanding lip 13 is braced by a web 16 thus preventing 90 danger of the lip being broken off. It will thus be seen that when the shaft 8 is rotated to swing the disks 10 and 11 upwardly, these disks will engage the lip 13 of the bracket 14 and the thickened portion 12 of the casting 5 and thus raise one side of the base.

In order to rotate the shaft 8, this shaft has been provided with a gear wheel 17 having its teeth cut to engage a worm 18 95 carried by a shaft 19 journaled in the bearing of the bearing bracket 20. This bearing bracket 20 is secured upon one of the cross bars 2 as shown in Figures 5 and 6 and will be securely held in place thus pre- 110

venting the worm 18 from moving out of engagement with the worm gear 17. A hand wheel 21 is provided for the shaft 19 so that this shaft can be easily rotated.

5 The table is provided with a lower section 22 and an upper section 23 having bearing sleeves 24 and 25 mounted as shown in Fig. 4 and receiving a bolt or pivot pin 26 so that the upper table section 23 may be rotated upon the lower table section. Rings 27 and 28 which form bearing races are carried by the table sections 22 and 23 and bearing balls 29 are positioned between these rings as shown, thus permitting the 15 upper table section to rotate very freely. It is desired to permit the upper table section to be locked in an adjusted position and therefore the upper ring 28 has been provided with ears 30 having openings formed 20 therein to receive a latching pin 31. This latching pin is slidably mounted in a socket 32 carried by a bracket arm 33 mounted upon the bolt or pivot stem 26 and extending beyond the edge of the lower table section. This pin 31 extends through the arm 33 and has its lower end portion provided 25 with an opening receiving the finger 34 of the lever 35 which lever is pivotally mounted beneath the arm and engaged by the spring 36 so that it will be yieldably held in the 30 position of Fig. 4 with the pin 31 extending through an opening of one of the side ears 30. An abutment block 37 is carried by this arm 33 and positioned between the bearings 38 of the bracket 39 so that when the pin 31 is positioned in the opening of one of the 35 ears 30, the adjusting screws 40 may be turned in their bearings 38 and the table given a slight rotation thus bringing the 40 stone into the proper position in case it is not placed straight upon the table. It will thus be seen that the upper table section may be turned to approximately the proper position and a final adjustment given which 45 will bring the stone into the desired position. This upper table section is formed in layers as shown, the lower layer having the sleeve 25 embedded therein and upper layer carrying corner blocks 41 upon which the 50 stone will rest and having its central portion cut out to provide a pocket 42 so that the securing nut 43 may be applied to and removed from the bolt or pivot stem 26.

In order to permit of the table being tilted 55 from a horizontal position to an inclined position, the table has its lower section provided with bearings 44 through which extends a shaft 45 mounted in bearings 46 carried by the bolsters 3 of the base. There- 60 fore, the table will be pivotally mounted and may be tilted to the desired angle. In order to support the table in a horizontal or tilted position, there have been provided cam disks 47 and 48 which are mounted upon 65 shafts 49 and 50 mounted in bearings 51 and

52 carried by the bolsters 3, the bearings 51 being mounted adjacent one end of the base and bearings 52 being mounted upon the reduced end portion of the side beams adjacent the cross bar or casting 5. From an 70 inspection of Figs. 3 and 4, it will be seen that the cam disk 47 extends in an opposite direction to the cam disk 48 and that therefore when the shafts 49 and 50 are rotated, the disks 47 will be swung upwardly while 75 the disks 48 are swinging downwardly. In order to impart rotary movement to the shafts, there has been provided a shaft 53 journaled in the bearing 54 of the bearing bracket 55 secured to one of the side beams 80 3. This shaft 53 which is provided with a turning wheel 56 carries worms 57 which engage the worm gears 58 mounted upon the shafts 49 and 50. By turning the shaft 53, rotary movement will thus be imparted to 85 the shafts 49 and 50.

When this improved table is in use, it is set up with the cam disks 47 and 48 in the position shown in Figures 3 and 4. The table should then be level. If it is found 90 that one side is lower than the other, this can be cured by shaft 8 and thus raising or lowering the side of the base carrying the bracket 14. After the table has been leveled, the stone will be put in place and one side 95 can be dressed. If it is found that the stone does not fit properly upon the table, a slight adjustment can be made by means of the set screws 40. After the stone is in place, the table will be tilted to bring the stone into 100 the proper position for cutting the beveled face, and after one side has been dressed, the latch will be released and the table given a quarter or half turn. The latch is again 105 locked and the second side of the stone dressed. It will thus be seen that the table may be placed at any desired angle and the stone easily dressed with all sides easily cut at the same level.

What is claimed is:

1. A stone working table comprising a base including spaced bolsters, a pivot shaft carried by the bolsters, a stone carrying table having a lower section mounted upon the pivot shaft for rocking movement, an 115 upper section rotatably connected with the lower section, and means carried by said bolsters for tilting the stone carrying table upon the pivot shaft and supporting the table in an adjusted position.

2. A stone working table comprising a base, a pivot shaft carried by the base, a stone working table having a lower section carried by the pivot shaft for rocking movement, and an upper section rotatably connected with the lower section, shafts rotatably connected with the base upon opposite sides of the pivot shaft, cam disks eccentrically connected with the last mentioned shafts and engaging the lower sec- 130

- tion of the stone carrying table with the disks of one shaft extending in an opposite direction to the disks of the second shaft, and means for rotating the disk carrying 50
5 shafts with the disks of one shaft moving in an opposite direction to the disks of the second shaft for rocking the stone carrying table upon the pivot shaft and supporting the table in an adjusted position.
10. 3. A stone working table comprising a base having side beams, bolsters carried by the side beams, a pivot shaft carried by the bolsters and extending transversely of the base, shafts rotatably connected with the 60
15 bolsters upon opposite sides of the pivot shaft, cam elements carried by the last mentioned shafts, a stone carrying table rockably mounted by the pivot shaft and engaged by the cam elements, and means 65
20 for rotating the cam carrying shafts to tilt the stone carrying table and support the same in an adjusted position.
4. A stone working table comprising a base, a stone carrying table having a lower 70
25 section pivotally connected with the base for vertical swinging movement and an upper section rotatably connected with the lower section, and means carried by the base and engaging the lower section of the 75
30 stone carrying table for tilting the table from a horizontal to an inclined position and supporting the table in the adjusted position.
5. A stone working table comprising a 80
35 base, and a stone carrying table carried by the base and having a lower section, an upper section, bearing plates carried by the upper and lower sections, a pivot pin carried by the upper section and extending 85
40 through the bearing plates and having a fastener positioned in a pocket formed in the lower section, and anti-friction means positioned between the upper and lower sections about the bearing plates.
45. 6. A stone working table comprising a base, a top having a lower section pivotally connected with the base and an upper section rotatably connected with the lower sec-
- tion, a bracket arm extending radially beneath the lower table section, a latch carried by said arm for engaging the upper table section, a bearing bracket carried by the lower table section and extending upon opposite sides of the bracket arm, and set screws carried by the bearing bracket for 55
engaging the arm and adjusting the arm and table.
7. A stone working table comprising a base, a top having a lower section pivotally connected with the base and an upper section rotatably connected with the lower section, a latch for releasably holding the upper section against rotary movement, the latch being adjustably mounted for giving final adjustment to the upper table section, 65
and means for tilting the table upon the base and releasably supporting the same in an adjusted position.
8. A stone working table comprising a foundation, a base resting upon the foundation and having one side movable vertically of the same, abutment elements carried by the base with one abutment serving as a bracing bar for the same, a shaft rotatably carried by the foundation, cams carried by said shaft and engaging the abutments for vertically adjusting one side of the base, a table having a lower section pivotally connected with the base for vertical tilting movement at right angles to 80
the movement of the base, means for tilting the lower table section and supporting the same in an adjusted position, and an upper table section rotatably connected with the lower table section.
9. A stone working table comprising a foundation, a base carried thereby and vertically tilttable from one side and a top carried by the base and having a lower section vertically tilttable at right angles to the 90
tilting of the base and an upper section rotatably carried by the lower section.

In testimony whereof I have hereunto set my hand.

HIRAM D. MORRILL.
